UNITED STATES PATENT OFFICE.

JAMES C. WHIPPLE, OF CHICAGO, ILLINOIS.

CURTAIN-STRETCHER STRUCTURE.

SPECIFICATION forming part of Letters Patent No. 772,687, dated October 18, 1904.

Application filed July 24, 1903. Serial No. 166,826. (No model.)

To all whom it may concern:

Be it known that I, JAMES C. WHIPPLE, a citizen of the United States, residing at Chicago, in the county of Cook and State of Illinois, have invented a certain new and useful Improvement in Curtain - Stretcher Structures, of which the following is a full, clear, concise, and exact description, reference being had to the accompanying drawings, forming a part of this specification.

My invention relates to curtain-stretchers, and particularly to the construction of bar and sliding pin therefor.

The object of the invention is to provide a simple, practical, inexpensive, and durable construction of bar and coöperating sliding pin.

In the accompanying drawings, Figure 1 is a perspective view of a portion of a curtain-stretcher bar and sliding pin embodying my invention. Fig. 2 is a cross-section of the same. Fig. 3 is a perspective view of the pin.

The curtain-stretcher bar A is desirably made of some suitable kind of wood and is made with a cut-away corner a. It is also provided with a slot a', which extends inwardly on a level with the horizontal face a², forming the lower side of the recess a'. The bar A is also provided with a vertical slot a³, 30 cut in the face or surface a².

The pin B comprises a base consisting of side portions b b, a front portion b', rear portions b² b³, and an upright pin proper, b⁴, connected by a portion b⁵ with the rear portion b³, the whole structure, base, and the pin proper being desirably made of a single piece of wire bent into the form described, as shown in Fig. 3. The front portion b' is lower than the remaining portions of the base, being connected with the sides b b by downwardly-extending portions b⁶ b⁶. The pin B fits upon the bar A, as shown in Figs. 1 and 2, the sides b b and rear portions b² b³ fitting into the slot a' of the bar and the front portion b' and 40 downwardly-extending portions b⁶ b⁶ fitting into the slot a³. The pins when so fitted upon the bar are free to slide longitudinally of the latter, as desired and required in curtain-stretcher structures. It will be seen that the 50 pin offers a firm resistance to being pulled

from the bar by the arrangement of the front portion b' in the slot a³. It will also be seen that the rear portion of the base being confined in the slot a' prevents the pin from being withdrawn by being lifted upwardly from 55 the bar. It will also be seen that the tensile strain on the pin is directly in a horizontal line along the portion b⁵ and sides b b and that consequently there is no tendency to bend the pin proper, as is often the case in stretcher- 60 bar constructions. It will also be seen that the sliding pin binds upon the bar in three places when the strain of the curtain is upon it: first, the front of the portion b' binds against the front of the groove a³; second, the 65 front of the portion b⁵ binds against the surface a²; and, third, the rear of the pin-base binds against the lower surface of the overhang of the bar. All this exercises a strong influence to hold the pin against sliding move- 70 ment.

It will be understood that changes and modifications can be made without departing from the spirit of my invention.

What I claim is—

1. The combination of a curtain-stretcher bar having a surface on which the pin-bases can rest and along which they can slide, said surface having a longitudinal slot or groove, means on the bar for engaging the pin-bases 80 in the rear of said slot, and a pin having a base arranged to rest and slide upon said surface and adapted to have its rear portion engaged by said means on the bar, the pin-base being provided with a lateral projection adapt- 85 ed to fit and slide in the slot in said surface, substantially as described.

2. The combination of a curtain-stretcher bar having a longitudinal surface for the pin-bases, and also having an overhanging portion projecting over the rear of said surface so as to form a slot or groove between said surface and overhang, said surface being also provided with a longitudinally-extending slot, and pins having bases adapted to rest and slide 95 upon said surface and to fit under said overhang in the rear of said slot, and constructed with lateral projections adapted to fit and slide in the slot in said surface, and located forward of the rear ends of the bases, whereby the pin- 100

bases are engaged by the overhang in the rear of their engagement with said slots, substantially as described.

3. The combination with curtain-stretcher pins provided with bases having lateral projections, of a curtain-stretcher bar having a surface on which the bases of said pins can rest and slide, said bar being provided with means for engaging the lateral projections on said pin-bases, and also with means for engaging the bases in the rear of said projections, substantially as described.

4. The combination of a curtain-stretcher bar A provided with a flat surface a^2 and an overhanging portion forming a slot a' between itself and the surface a^2 , the latter being provided with a longitudinal slot a^3 , and curtain-stretcher pins B having bases adapted to fit between the surface a^2 and said overhang and constructed with a downwardly-extending projection b^6 , b^6 and b' adapted to fit and slide in the slot a^3 , and located forward of the rear end of the bases, substantially as described.

5. The combination of a curtain-stretcher bar having a corner cut away to form a flat surface a^2 provided with a slot a^3 , said bar being also constructed with an overhang forming between itself and the surface a^2 a slot a' , pins B, each consisting of a base formed by sides b , b , rear portions b^2 , b^3 , a downwardly-extending front projection formed near the front of the base of portions b^6 , b^6 and b' , and a pin proper b^4 connected by a portion b^5 with the rear portion b^3 , substantially as described.

6. A curtain-stretcher bar constructed with a surface for the pin-bases, said surface being provided with a longitudinally-extending slot or groove located between the front and rear of said surface, substantially as described.

7. A curtain-stretcher bar provided with a surface for the pin-bases, said surface being

provided between its front and rear with a longitudinally-extending slot or groove, and the bar being provided with means for engaging the pin-bases in the rear of said slot, substantially as described. 45

8. A curtain-stretcher bar constructed with a surface a^2 having a slot a^3 between the front and rear of said surface, and also constructed with an overhanging portion forming between itself and the surface a^2 a slot a' , substantially as described. 50

9. A pin for curtain-stretchers comprising a pin proper, a pin-base carrying the pin, said base being provided with a lateral projection between its front and rear, substantially as described. 55

10. A pin for curtain-stretcher bars comprising a pin proper, a base carrying the pin, and a downwardly-extending projection carried by said base between its front and rear, substantially as described. 60

11. A pin for curtain-stretcher bars comprising a pin proper b^4 , a base carrying the pin proper, and a downwardly-extending projection consisting of portions b^6 , b^6 and b' , said projection being located between the front and rear of the base, substantially as described. 65

12. A pin for curtain-stretcher bars comprising a pin proper b^4 , and an integrally-formed base consisting of a portion b^5 , sides b , b , rear portions b^2 , b^3 , and a downwardly-extending projection consisting of portions b^6 , b^6 and b' , said projections being located between the front and rear of the base, substantially as described. 70 75

In witness whereof I hereunto subscribe my name this 21st day of July, A. D. 1903.

JAMES C. WHIPPLE.
